[57] CLAIM

The ornamental design for speaker grill, substantially as shown.

DESCRIPTION

FIG. 1 is a front elevational view of a speaker grill showing my new design;

FIG. 2 is a bottom plan view of FIG. 1, the top being a mirror image thereof;

FIG. 3 is a side elevational view of FIG. 1, the opposite side being a mirror image thereof; and

FIG. 4 is a sectional view taken along line 4—4 in FIG. 1.
